UNITED STATES PATENT OFFICE

JOHN F. STRAITZ, OF PHILADELPHIA, PENNSYLVANIA, ASSIGNOR TO NATIONAL AIROIL
BURNER COMPANY, INCORPORATED, A CORPORATION OF DELAWARE

CHAR RETORT

Application filed June 17, 1931. Serial No. 544,961.

My invention relates to improvements in char retorts. The object is to provide a construction, having a maximum strength and also an increased exterior area exposed to the heat of the kiln and an increased interior area exposed to the char. The construction also comprises sections and means for assembling the same whereby a section may be removed, in case it has become distorted or ineffective, and a new section substituted in its place.

The construction, in accordance with my invention, provides a retort having a strength and life in the ratio of about four to one, as compared with the retorts now in common use, and presents correspondingly increased outside and inside heating surfaces, with its maximum diameters substantially the same as that of retorts now in common use.

20 The construction, in accordance with my invention, may also provide means whereby the char is made to travel in a helical path of travel, thereby improving the quality of the product delivered thereby.

25 Referring to the drawings which illustrate, by way of example, preferred embodiments of the invention:—

Fig. 1 is an elevation of a complete retort showing straight corrugations.

30 Fig. 2 is a similar view showing helically extending corrugations.

Fig. 3 is a cross-section, on an enlarged scale, on line 3, 3 of Fig. 1.

Fig. 4 is a similar cross-section on line 35 4, 4 of Fig. 2.

Fig. 5 is a top plan view of construction shown in Fig. 1, also on an enlarged scale.

Fig. 6 is a fragmentary section on line 6, 6 of Fig. 5.

40 Fig. 7 is a view in perspective of the assembling sleeve.

Fig. 8 is a fragmentary cross-section similar to Fig. 3, but showing the outer surface of the retort plain, instead of corrugated.

45 Fig. 9 is an elevation, on a reduced scale, showing a section with straight corrugations combined with a section with helical corrugations.

50 Figs. 10 and 11 are fragmentary sections in vertical planes at right angles with each

other, showing the association of the retorts with the kiln, the scale being further reduced.

Fig. 12 is a fragmentary vertical section of the upper retort section, shown in Fig. 2, showing the interior surface of the same. 55

Similar numerals refer to similar parts throughout the several views.

In the char retorts now in common use in sugar refineries the retort is of cast iron, of oval form in cross-section, the cross-section dimensions being about six and a half inches by fourteen inches. The length of the retort is usually about eight feet. These retorts have a smooth surface both inside and outside, and the walls are about three quarters of an inch thick. When subjected to the intense heat of the kiln the retort is liable to buckle, thereby causing delay and expense in renewing.

50 In accordance with the present invention the retort unit is made in two sections, each about four feet long. These sections are provided with smooth oval flanges or reduced end portions 9 at top and bottom and are secured together by a sleeve 10 of length about double the length of a flange. As shown in Figs. 5 and 6 the inner corrugations 11 may be made to taper toward the flanges.

55 The maximum outer cross-sectional dimensions of the retort, in accordance with my invention, is substantially the same as in the retorts now in common use, that is about six and a half inches by fourteen inches, and the normal thickness of the walls is about three quarters of an inch. As shown in the cross-sectional views however, the walls are formed with corrugations 12 running from top to bottom of the retort. These corrugations may be straight, as shown in Fig. 1, or they may be helical, as shown in Fig. 2. While the arc-shaped formations 12 of the wall are about three quarters of an inch in thickness, it will be noted that, with respect to the inner surface, these arc-shaped formations are developed into planes joining at an acute angle, 95 thereby forming ridges 11 (or points in cross-section) extending into the retort chamber 13. These ridges may be staggered, as shown in Fig. 3, or they may be oppositely disposed, as shown in Fig. 4; in either case, it will be 100

noted that these ridges 11 are of greater radial wall thickness than that of the arc-shaped portions 12 of the wall. These ridges 11 therefore not only form strengthening strips which contribute largely to the prevention of the buckling above referred to, but also provide an interior wall area equal to or slightly greater than the exterior wall area. They thus present large heating surfaces in 10 the inner wall surface of the retort chamber 13. The thickness of the ridge portions 11 is increased by the joinder of the outer faces of the arc-shaped formations 12, which joinder is in the form of a reversed arc 14. 15 The sleeve 10, which fits over to adjacent or abutting reduced end portions or flanges 9, extends to the outer margin of the arc-shaped formations 12, thus forming the completed retort as shown in Figs. 1 and 2. 20 Figs. 10 and 11 are fragmentary sections of a conventional kiln showing the retorts therein. The reduced upper end portions or flanges 9 engage with suitable feeding spouts of the char pocket 15. The reduced lower 25 ends of the retorts are shown engaged with and delivering to discharge and cooler pipes 18. The flues for burnt products are shown at 20. A fuel oil burner is shown at 21, in Fig. 11, and peep holes are shown at 17. 30 *In operation.*—These retort units in accordance with my invention, which are formed preferably of two sections coupled together with a sleeve, are adapted to be fitted into the standard kilns, and to cooperate with the feeding and discharging elements associated therewith.

The increased outer surface exposed to the heat of the kiln and the still greater increased interior surface to which the char is exposed, 35 greatly increase the efficiency of the action of the heat upon the char passing therethrough. The reinforcing portions of the retort formed by the inner surfaces of the arc-shaped portions developed into planes 40 joining at acute angles and thereby forming the ridges 11, contribute greatly to prevent distortion and buckling, and thus add substantially to the life of the retort. The smooth development of the curved surfaces 45 between the channel-ridges of the interior wall surface facilitates the passage of the char through the retort without clogging. The removable sections make possible the substitution of a new for a damaged section 50 of a retort and thus greatly reduces labor and expense which would otherwise be involved in replacing the entire retort. The helical formation of the interior ridges and channels causes a whirling of the char, carrying more 55 material to the walls of the retort and thus securing a more efficient treatment and finer product.

It has been found that the combination of sections, the upper with straight longitudinally extending ridges and channels and the

lower with helical ridges and channels, as shown in Fig. 9, has decided advantages, because when the char enters the top of the retort it is wet and liable to cake and choke the retort where the ridges and channels are of helical form, whereas, if the ridges and channels of the upper section or portion are straight, the char passing therethrough is sufficiently heated and dried to respond to the whirling action due to the helical ridges and channels of the lower section or portion without danger of clogging. 70 75

It will also be understood that the inner corrugations or ribs and channels are the more important, as providing maximum heating surface acting upon the char, and that the outer side or surface of the retort may be smooth or plain, that is without corrugations, as in Fig. 8, and still have substantial efficiency. 80 85

What I claim is:—

1. A vertical retort comprising elongated tubular sections, each section having at each end reduced end portions, a cooperating separable sleeve adapted to receive a reduced end of each of two of said sections when the two sections are brought into vertical alignment and abutting with one end of one of the two sections resting upon one end of the other section, and all of said reduced end portions of said sections having the same dimensions so that said sections are independently removable and replaceable with either end up-permost. 90 95

2. A vertical char retort having, as to its interior wall surface, substantially parallel longitudinally extending channels arranged side by side and having the surfaces of each two of the adjacent channels meet each other in an acute angle and the bottom portions thereof are shaped in cross-section, and merging at the opposite sides thereof, into other surfaces, the adjacent other surfaces joining each other and thereby forming said acute angles so that the width across each of the channels increases progressively from the bottom portion thereof to the two acute angles at the opposite sides of the channel, and the exterior wall surface of the retort so formed and disposed, relatively to said interior wall surface, that the thickness of the retort wall at the ridges is approximately double that of the intermediate wall portions, as and for the purpose specified. 100 105 110 115 120

3. A vertical char retort having, as to its interior wall surface, substantially parallel longitudinally extending helical channels arranged side by side and having the surfaces of each two of the adjacent channels meet each other in an acute angle and the bottom portions thereof are shaped in cross-section, and merging at the opposite sides thereof, into other surfaces, the adjacent other surfaces joining each other and thereby forming said acute angles so that the width across 125 130

each of the channels increases progressively from the bottom portion thereof to the two acute angles at the opposite sides of the channel whereby material when passing through 5 the retort may be given a whirling motion.

4. A vertical retort, comprising an upper tubular section and a lower tubular section secured together end to end, the upper section having, as to its interior wall surface, sub-

stantially parallel straight channels and ridges extending substantially longitudinally of said section, the lower section having, as to its interior wall surface, substantially parallel helical channels and ridges extending substantially longitudinally of said lower section. 70
